UNITED STATES PATENT OFFICE.

SAMUEL DAY AND REASON DAY, OF DELAVAN, ILLINOIS.

CULTIVATOR.

SPECIFICATION forming part of Letters Patent No. 274,920, dated April 3, 1883.

Application filed August 14, 1882. (No model.)

To all whom it may concern:

Be it known that we, SAMUEL DAY and REASON DAY, of Delavan, in the county of Tazewell, in the State of Illinois, have invented an Improvement in Cultivators; and we do hereby declare that the following is a full, clear, and exact description thereof, reference being had to the annexed drawings, making a part of this specification, in which like letters of reference refer to like parts, and in which—

Figure 1 represents a plan; Fig. 2, a side sectional view.

This invention is an improvement upon a cultivator patented by Samuel Day, November 10, 1868, No. 83,838, and relates to a means of changing the direction of the line of draft of the cultivator relative to the tongue, for the purpose of guiding the machine.

The object of this invention is to produce the maximum variation between the cultivator and its tongue with the minimum movement of the hand applying the force consistent with the amount of strength convenient to be used.

B B' represent part of the frame-work of the cultivator, and A the tongue, pivoted at O to the bar B, and sliding between the bar B' and the cast-metal bridge C, which is bolted at its ends to said bar B'. Said bridge C has upon the upper side, at its center, a boss, J, and in line behind it, with their centers about two inches apart, a second boss, having through its center a bolt-hole countersunk beneath. The boss J must be no higher than the base of the perforated boss K. The link E, which we make about one foot long, has at one end a slot, G, at the other end an opening to fit the boss J, and at about four inches from said opening a hole for the bolt F. The T-shaped link D is pivoted upon the boss K, being held thereat by the bolt and washer H. To the ends of the arms are fastened rods R R, which come together as they leave said link D, and are secured in the handle S. Through the slot M goes the bolt F, which holds together the two links D and E. A bolt fastened into the tongue A projects up through the slot G of said link E, and the link D, being over the

link E, prevents the latter from coming off from its boss J.

By the addition of the link E it is evident that more of an angular variation is obtained between the cultivator and its tongue A than if the slotted end of the link D were pivoted to the tongue. By shortening the distance between the two bosses J and K, the throw of the end G of the link E is decreased, and by lengthening said distance the throw of said link E, and consequently of the tongue A, is increased. If the throw of the tongue A relative to the handle S is increased too great a degree, so much strength will be required to move said handle S as to make the cultivator difficult to guide. By experiment we have found the proportions given above to be practically the best.

In operating this cultivator the driver, who sits upon a seat directly behind the pivotal point O of the tongue, grasps with one hand the handle S, holding it in line with the line of draft of the cultivator if he desires to go straight ahead, but pressing it to one side or the other, according to which side he wishes to steer the cultivator.

What we claim as our invention, and for which we desire Letters Patent, is as follows:

1. The tongue A, cultivator-frame B B', and bridge C, in combination with the link D, having slot M, rods R R, and handle S, and the link E, having slot G and bolt F, substantially as and for the purpose set forth.

2. A cultivator-frame, B B', tongue A, pivoted thereto, and bridge C, having bosses J and K, in combination with the slotted link E, having bolt F, and slotted link D, having a moving-lever.

In testimony that we claim the foregoing invention we have hereunto set our hands this 31st day of July, 1882.

SAMUEL DAY.
REASON DAY.
